CLAIM

The ornamental design for a mascara and brush container, as shown and described.

DESCRIPTION

FIG. 1 is a front view of a mascara and brush container showing the new design.

FIG. 2 is rear view thereof.

FIG. 3 is a left side view thereof, the right side view being a mirror image of FIG. 3.

FIG. 4 is a top view thereof.

FIG. 5 is a bottom view thereof.

FIG. 6 is an exploded front view thereof showing the mascara brush; and,

FIG. 7 is a front, top and left side perspective view thereof. The broken lines shown in the FIGS. 1, 6 and 7 illustrate portions of the article that form no part of the claimed design.
